WHEEL FLANGE AND RAIL LUBRICATOR

John O. Madison, Brooklyn, N. Y., assignor to
Chillingworth Manufacturing Company, Jersey
City, N. J., a corporation of New Jersey

Application January 12, 1934, Serial No. 706,344

18 Claims. (Cl. 184—3)

This invention relates to wheel flange and rail lubricators.

The principal object of the invention is to provide simple and durable means for efficiently applying lubricant to the flanges of rolling car wheels preparatory to their travel along the curve rails, including guard rails, of a railroad track, to the end that a film of oil shall be carried by the wheel flanges and distributed thereby upon the 10 opposing side or sides of the curved rail heads in such manner as to prevent excessive friction between the contacting surfaces, thus obviating objectionable noises and also reducing the wear on the rail heads and wheel flanges under service conditions.

Other subsidiary objects of the invention will hereinafter appear.

In the embodiment of my invention herein illustrated, a trough of suitable length, (determined by the circumference of the wheel flange to be lubricated) is arranged alongside a rail immediately preceding the curve thereof, which trough is of sufficient capacity, either in itself or through additional supply means, to ensure 25 the delivery of the requisite quantity of oil for lubrication during a predetermined period. Within the trough is supported a longitudinally extending body of absorbent material, such, for example, as wicking, which rises above the trough 30 and presents to the path of the rolling wheel flange a laterally-resilient contact surface or surfaces effective to apply oil progressively to the flange. The absorbent material is sustained throughout the length of the trough by inherently 35 resilient frame structures. At the respective ends of these structures are longitudinally-projecting laterally-deflected members which afford flaring entrances for the approaching wheel flange, thus insuring the initial guidance and spreading of 40 the absorbent material by the entering flange against the elasticity of the frame structures.

The invention also comprises features of construction and combinations of parts, all of which will be hereinafter described and the scope of 45 the invention then expressed in the appended claims.

In the drawings—

Figure 1 is a transverse vertical section through the lubricator as mounted adjacent a rail. 50 Fig. 2 is a partial plan of the lubricator and rail shown in Fig. 1, the oil-applying fabric being partly removed.

Fig. 3 is a view similar to Fig. 1, showing the 55 embracing action of the lubricator on the flange of a car wheel.

Fig. 4 is a vertical section, as on the line 4—4 of Fig. 3.

Fig. 5 is a plan of a portion of a railroad track equipped with lubricators adjacent the respective rails at the approach to a curve.

Fig. 6 is a slightly modified form of the apparatus for efficiently applying lubricant to one side only of the wheel flange.

Referring to the drawings, 10 designates an elongated lubricant container or trough comprising a bottom, sides and ends, which container is illustrated as arranged adjacent and longitudinally of the inner side of a track rail 11 at the approach to a curve having a guard rail 110. In the present instance the outer wall 12 of the 70 container is upwardly extended and bolted at its respective ends on suitably-spaced angle brackets 13 affixed to the adjacent cross-ties, a spacer bar 130 being interposed between the other wall and the rail.

A plurality of rows of bolt holes 14 in different planes are preferably formed in the upstanding member of each of the brackets, so that by entering the bolts 15 in the upper or lower row of holes, the trough and its appurtenances can be 80 positioned at different levels in respect to the top of the adjacent rail head, as desired.

At the bottom of the trough is arranged a pipe 16 which extends medially of the trough throughout substantially the length of the latter, which pipe is securely, yet detachably, held in place by a series of spring clips 17 fastened at intervals upon the bottom of the trough. This pipe communicates at its ends by means of pipe connections 19 with an oil reservoir 20 which is conveniently 90 supported above the road bed and in proximity to the trough by means of U-bolts 21 mounted in the upstanding members of angle brackets 22 which are associated with the brackets 13. Each of the connections 19 includes a suitable coupling 95 23 whereby the connection can be detachably joined to the adjacent end of the pipe 16, and it also includes a suitably-disposed valve 24 effective to open or close the connection in order to permit or check the flow of oil from the reservoir to the trough as occasion may require. The reservoir is provided with an outwardly extending oil supply pipe 240 whereby the reservoir can be replenished from a remote point.

The oil reservoir 20 and its connections 19 with the pipe 16 may be omitted, removed or replaced, as desired, in which case the trough can be directly supplied with oil in any suitable manner as requirements may demand.

The pipe 16, which, in the present instance, is 110

provided at intervals throughout its length with suitable orifices 160 for the discharge of oil, supports throughout its length a succession of spaced pairs of upstanding inherently elastic supporting members 25 which rise above the level of the oil within the trough and somewhat below the top of the adjacent rail head. Each pair of members is preferably composed of a single piece of spring metal of substantially U-formation, the base

10 thereof embracing and closely hugging the pipe so as to have capacity for limited rocking movement about an axis longitudinally of the pipe.

The succession of spring supporting legs on each side of the pipe are connected at their upper ends by a longitudinally extending spring-metal strip 26 which is welded or otherwise firmly secured to each of the legs. This strip terminates in longitudinally-twisted laterally-deflected extensions 27 which project beyond the respective 15 ends of the trough, and which extensions are preferably separate spring members also welded or otherwise firmly united to the respective strips. The complementary spring extensions thus afford at each end of the trough a flaring entrance to 20 the space between the spaced longitudinal strips 26, the sides of which entrance, upon the impact thereon of the flange of an approaching wheel, effectually guide and aline the adjacent spring supports to position one leg and its longitudinal 25 strip on each side of the flange in any lateral position that the flange in its travel may assume in relation to the adjacent side of the rail head.

The upstanding U-shaped spring members 25 and their associated longitudinal connecting strips 26 constitute, in effect, two juxtaposed inherently-elastic skeleton frames which extend longitudinally of the trough, such strips 26 being maintained normally in spaced parallel relation above the trough by the inherent elasticity of 30 the spring members. The pipe 16, together with the associated frames, can be readily applied to or removed from the supporting clips 17 within the trough.

Each of the skeleton frames is provided 35 throughout its length with a covering of absorbent material 28, such as felt or wicking, which depends into the oil contents of the trough so as to feed oil effectively to the upper portions of the covering enveloping the strip 26.

40 As seen in Figs. 1 and 3, the fabric is folded upon and along the skeleton frames to provide an M-shaped covering which embraces the upper edges and inner and outer sides of the frames, and includes inner converging folds 29 extending into the oil contents of the trough, and also two outer lateral folds 30 depending loosely into the contained oil.

From the foregoing described construction and organization it will be seen that when a car 45 wheel approaches the railroad curve adjacent to which the structure is mounted, the flange of the wheel passes to and between the opposing flaring extensions 27 at the entrance end of the trough, and thus bears against the opposing sides of the extensions in a manner effectually to guide and aline the proximate portions of the skeleton structures with respect to the path of the wheel flange and thereby efficiently position such portions at the respective sides of the flange in any 50 lateral relation to the adjacent rail head that the flange may occupy in its travel. The flange, as the wheel progresses above the trough and toward the track curve, rolls between and is uniformly and snugly embraced by the spring-pressed oil containing fabric on the upper por-

tions of the skeleton frame structures. As a result the fabric effectually applies a film of oil to and throughout a circumferential area on the respective sides of the flange, and consequently one or the other side of the wheel flange carries its oil film to the opposing side of the head of the contiguous curve rail or guard rail of the track as the case may be, thus preventing excessive friction between the contacting flange and rail surfaces, as previously mentioned.

80 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

85 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

90 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

95 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

100 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

105 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

110 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

115 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

120 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

125 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

130 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

135 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

140 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

145 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

150 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

155 The outer acting surfaces of the oil-applying fabric with which the wheel flange comes in contact during its travel, are provided with an interstitial metal covering 31 which serves to protect the fabric from severe abrasive action by the flange, and also yields to the progressing lateral pressure thereon of the flange to permit the free exudation of the oil from the fabric to and against the contacting surfaces of the flange. This protective covering in the form shown comprises a series of substantially parallel wires, (such as are commonly used for belt jointing) disposed diagonally in narrowly-spaced relation along the oil applying surfaces of the fabric throughout its length.

- ing member at intervals throughout its length, and longitudinally extending strip members uniting the upper ends of the succeeding legs on the respective sides of the spring elements and terminating in flared end extensions, and absorbent material covering said strip members and supported and reinforced thereby so as resiliently to embrace a wheel flange as it travels along the rail, said material depending into the container.
- 10 15. A lubricant applying device embodying an elongated lubricant container arranged laterally adjacent a rail, a pipe arranged at and longitudinally of the bottom of the container, said pipe having oil discharge orifices at points throughout its length, means for supplying oil to said pipe, an upstanding resilient structure extending longitudinally of the container and supported at its base by said pipe, and absorbent material extending longitudinally of the container and supported and reinforced throughout its length by said structure in the path of a wheel flange as it travels along the rail, said material depending into the container.
- 15 20. 16. A lubricant applying device embodying an elongated lubricant container arranged laterally adjacent a rail, spaced clips on the bottom of the container, a rigid supporting member extending longitudinally of the container and detachably held by said clips, an upstanding resilient structure extending longitudinally of the container and mounted at its base on said supporting member, and absorbent material extend-
- ing longitudinally of the container and supported and reinforced throughout its length by said structure in the path of a wheel flange as it travels along the rail, said material depending into the container.
